[57] CLAIM

The ornamental design for a multi-purpose floatation device,
as shown and described.

DESCRIPTION

FIG. 1 is a front elevational view of a multi-purpose floatation device showing my new design, portions of the strap being broken away to indicate indeterminate length;
FIG. 2 is a rear elevational view thereof;
FIG. 3 is a left side elevational view thereof;
FIG. 4 is a right side elevational view thereof;
FIG. 5 is a top plan view thereof; and,
FIG. 6 is a bottom plan view thereof.
